UNITED STATES PATENT OFFICE.

RUDOLF SCHNABEL, OF BERLIN, GERMANY, ASSIGNOR TO MINIMAX ACT.-GES., OF BERLIN, GERMANY.

PROCESS OF GENERATING FOAM FROM FOAM-DEVELOPING SUBSTANCES.

No Drawing. Application filed April 23, 1927, Serial No. 186,164, and in Germany September 30, 1925.

My invention relates to a process of producing foam for extinguishing fires which have broken out in oil or gasoline tanks and similar conflagrations which cannot be 5 extinguished by means of water.

The new or improved process is based upon the observation that liquids which are under pressure strongly oversaturated with carbonic acid release the largest portion of 10 the combined or dissolved carbonic acid again as soon as the pressure is removed. In liquids like beer the release of the carbonic acid is accompanied by a copious development of foam.

15 The utilization of this phenomenon in my improved process takes place substantially in the following manner: A tank filled with a liquid capable of developing foam, for instance a solution of saponin, is put in communication with a steel bottle containing liquid carbonic acid until the saponin solution has absorbed the quantity of carbonic acid corresponding with the pressure prevailing whereupon the tank is closed by a 20 cock. If this cock, which may be connected with a hose with nozzle, is opened a vigorous ebullition of the foam generating liquid takes place owing to the sudden relief of the pressure and in consequence thereof a strong 25 development of foam, as extensive experiments have proved.

Whether the foam developed is allowed to escape merely by opening the cock or through an ascending pipe line is a question

of suitability only. It is, furthermore, quite 35 immaterial to the principle of my invention whether a gas other than carbonic acid capable of absorption is employed or whether for the purpose of increasing the effect of the foam developing liquid substances are 40 added to the liquid which promote the absorption or liberation of the carbonic acid either mechanically, chemically or catalytically.

Various changes and modifications may 45 be made in my process without departing from the spirit of my invention and I desire, therefore, that the claims should be read as limited by the state of the art only.

I claim as my invention:—

50 1. The process of generating foam from foam developing substances, which consists in oversaturating a saponin solution with a gas capable of being absorbed, in a container under pressure, in such a manner that on 55 relieving the pressure the absorbed gas is liberated again and develops foam in conjunction with the liquid.

2. The process of generating foam from 60 foam developing substances, which consists in oversaturating a saponin solution with carbonic acid gas in a container standing under pressure, so that on relieving the pressure the carbonic acid gas is liberated and 65 forms foam in conjunction with the saponin solution.

RUDOLF SCHNABEL.
